UNITED STATES PATENT OFFICE.

CHARLES A. BAILEY, OF CROMWELL, CONNECTICUT, ASSIGNOR TO THE
J. & E. STEVENS COMPANY, OF SAME PLACE.

DESIGN FOR A TOY MONEY-BANK.

SPECIFICATION forming part of Design No. 29,687, dated November 15, 1898.

Application filed October 6, 1898. Serial No. 692,855. Term of patent 31 years.

To all whom it may concern:

Be it known that I, CHARLES A. BAILEY, a citizen of the United States, residing at Cromwell, in the county of Middlesex and State of Connecticut, have invented and produced a new and original Design for Toy Money-Banks, of which the following is a specification, reference being had to the accompanying drawing, forming part thereof.

10 The object of my invention is to produce an original and unique design for a toy bank which shall not only be useful as a receptacle for coin, but will also present a pleasing appearance and provide an ornamental device,

15 the general shape and configuration of the bank being a near resemblance to a warship, and the essential features upon which I claim protection are hereinafter particularly specified.

20 Referring more particularly to the said drawing, the essential features of my design for a toy bank which especially characterize the same are a box or receptacle A, having substantially vertical sides *a*, which are

25 curved outward longitudinally and meet at their ends, resembling the hull of a marine vessel; a top plate B, connecting the upper ends of the side pieces; cylindrical portions C, in imitation of turrets, extending upward

30 from the top plate B, said cylindrical portions having projections *c*, imitating the muzzles of cannon, and vertical tubular projections *c'* to represent smoke-stacks, and a post or upright D, reduced in diameter at intervals to have the appearance of a military mast.

The upper end of the side pieces of the box or body of the bank are extended laterally from about the center rearward, as shown at *e*, while the lower part has a peculiar-shaped projection *f* and rearwardly - projecting 40 straight portion *f'*. The forward end of the side pieces are each extended or curved upward, as shown at *g*, and provided with holes *g'*, from one of which extends a chain *h*, connected to an anchor *h'*, the latter being located partly on the top plate B. The side pieces *a* are provided with longitudinal parallel lines *i*, connected at intervals by vertical lines *i'*, and along the aforesaid lines, adjoining the same, are disposed dots or small 50 projections *k*, representing bolt-heads. The upper ends of the tubular projections *c* have annular flanges or beads *l*, and the upright or military mast has similar beads *l'* at the upper end of each section, excepting the top 55 section.

In the top plate B, in front of the forward turret, is a coin-slot *m*, through which the coins are passed into the body or receptacle.

Having described my invention, what I claim as new, and desire to secure by Letters Patent, is—

The design for a toy money-bank, as herein shown and described.

CHAS. A. BAILEY.

In presence of—

ARTHUR BOARDMAN,
GEO. P. SAVAGE.
